STEAM GENERATOR

Jesse Dee Tucker, Patterson, Calif.

Application October 22, 1953, Serial No. 387,727

5 Claims. (Cl. 122—208)

This invention relates to new and useful improvements in steam generators, and more particularly relates to a generator for producing high pressure, superheated steam.

One respect in which the present invention is distinguished from other steam generators is that the water entering the generator is initially vaporized by injection through a high-pressure nozzle having a relatively small orifice which breaks up the water into a fog of fine particles. Vaporization of the water improves the efficiency of the generator in the sense of utilizing the heat of the fuel more completely.

The water vapor and steam are passed through a circuitous narrow passageway, the walls of which are heated by hot gases and the flame of a burner. The hot gases produced by the burner likewise travel a circuitous passageway and there is an intimate and prolonged contact of the hot gases with the walls of the steam passageway.

One of the features of the invention is the provision of a tier of pairs of plates, the meeting surfaces of the plates providing very thin passageways through which the water vapor and steam travel. Alternate pairs of plates are annular and circular in shape, the vapor first passing radially outwardly in the uppermost plate (which is circular), thence downwardly to the outside of the second pair of plates (which is annular), then horizontally inwardly of the second pair of plates, then downwardly and inwardly of the third highest pair of plates (which is circular), and alternately inwardly and outwardly as the steam progresses downwardly in the generator.

The peripheries of the circular plates are spaced inwardly from the inner walls of the shell of the generator thus providing a space for the passage of hot gases whereas the peripheries of the annular plates are in contact with the interior of the shell of the generator, thus directing the gases through the opening in the center of the annular plates. From the foregoing, which is hereinafter described in greater detail, it will be seen that the passage of the gases thus likewise is circuitous.

The result of the construction of the plates is the provision of a simple and inexpensive generator having a low fuel consumption and producing a very large volume of steam for a small weight and volume of generator unit.

Further, there is no danger of cracking the equipment because water enters the generator in a vapor state, thus eliminating the danger of conventional boilers which may crack upon injection of a stream of cold water.

The steam generator which is the subject of this application is less dangerous than other steam generators because it contains no hot water under pressure, but on the contrary, contains only water vapor. The water which makes up the steam enters the generator in a high pressure spray jet in vapor state and this greatly reduces the danger of explosions which may occur in other steam generators and boilers. Thus the present generator can be used by unskilled personnel and under conditions which have heretofore precluded the widespread use of steam generators of this general type such as in motor cars and the like.

The steam generator hereinafter described has a down draft whereby the draft is automatically controlled to maintain an even temperature within the generator. It will be understood that the generator may incorporate a pilot flame which ignites the burner so that it may be turned on and off at any time. This enables the generator to be held at an even temperature and makes the device responsive to a manually controlled throttle in the steam discharge line.

Other objects of the present invention will become apparent upon reading the following specification and referring to the accompanying drawings in which similar characters of reference represent corresponding parts in each of the several views.

In the drawings:

Fig. 1 is a vertical midsection through the device.

Fig. 2 is a horizontal section taken substantially along line 2—2 of Fig. 1.

Fig. 3 is a horizontal section taken substantially along line 3—3 of Fig. 1.

The present invention employs a cylindrical steel shell 11, suitably insulated by means of glass wool or other insulation 12 on the exterior, in and upon which the other elements of the generator are mounted. At the top of the shell is a down-draft gas burner 13, the burner being annular in shape with the jets 14 of the burner directed downwardly inside the casing 11. Gas and primary air enter through pipe 16. A manifold 17 surrounds the casing below the burner, the manifold communicating with the interior of the burner by means of ports 18 in the casing wall. Air enters the manifold and the interior of the casing through air inlet duct 19, the flow of air being regulated by damper 21, which is manually or automatically controlled by means hereinafter described. The primary air and secondary air entering through ports 18 support combustion in the combustion chamber 22, the hot gases passing downwardly in a circuitous path as hereinafter more fully set forth and being drawn off through a flue 23 connected to the bottom plate 24 which closes off the lower end of the casing. A damper 26 in the flue 23 likewise regulates the flow of combustion gases through the generator. The burner construction of the generator is subject to considerable variation, the above-described structure being a presently preferred construction.

Mounted in the casing below the combustion chamber 22 is a tier of horizontally stacked pairs of plates. Each plate of each pair of plates is spaced apart a short distance from its mate, there being a thin passageway through which steam or water may pass from the water inlet located at the top of the generator to the steam outlet at the bottom of the generator. The topmost pair of plates 31 and 32 is mounted immediately below the combustion chamber 22, the upper plates 31 being provided with an upwardly extending inlet riser 33 which receives water discharged from nozzle 34 as hereinafter set forth. Located in the inlet riser 33 is a deflector 36, conical in shape, which deflects the water radially outwardly through the narrow passageway 37 between the upper plate 31 and the lower plate 32. Adjacent the periphery of the pair of plates is an annular enlarged collector ring 38 in which water vapor and steam collects. It will be noted, particularly with reference to Fig. 2, that an annular space 39 exists around the periphery of the topmost pair of plates 31 and 32, the hot gases of the combustion chamber passing downwardly through this annular space. The second pair of plates 41 and 42, positioned below the topmost plates 31 and 32, are substantially annular in shape, the uppermost plate 41 being joined to the interior of the cylindrical casing 11 to act as a baffle so that hot gases are directed inwardly and thence through the circular hole 43 at the center of the annular plates. The annular

second series of plates has an annular collector ring 44 near its periphery which is connected by a plurality of vertical pipes 46 with the ring 38. A second or inner collector ring 47 is formed between the second pair of plates adjacent the inner diameter thereof. Between the first and second annular rings 44 and 47 is a thin passageway 48 through which vapor and steam pass, it being understood that the passageway 48 may be corrugated rather than straight as is the case of the passageway 37 of the uppermost pair of plates.

The third pair of plates 51 and 52 positioned below the second pair is circular rather than annular, there being a gap 53 around the periphery of the third pair of plates between the periphery and the inside of the casing 11 so that the gases which pass through the hole 43 in the center of the second pair of plates are directed around the outside of the third pair of plates. The third pair of plates has an inner collector ring 54 which is connected by means of pipes 56 to the inner ring 47 of the second pair of plates. The third pair of plates likewise has an outer collector ring 57 and the inner and outer rings are connected by a thin passageway 58 between the two plates 51 and 52 which, if desired, may be corrugated in shape.

The fourth pair of plates resembles the second pair 41 and 42 in shape and function, and the fifth pair resembles the third 51 and 52, alternate pairs of plates being substantially the same.

The lowermost pair of plates 51 and 52 is connected directly to the steam outlet 59 by means of pipe 61 connected to ring 57.

From the foregoing description of the pairs of plates which are disposed inside the cylindrical casing 11, it will be observed that the flow of hot gases from the combustion chamber 22 down to the outlet flue 23 is circuitous in that the gases pass around the outside of the first pair of plates 31 and 32 and then through the hole 43 in the center of the second pair of plates 41 and 42 and thence outwardly through the gap 53 at the periphery of the third pair of plates 51 and 52, and alternately thereafter around the periphery and through the center of the various pairs of plates. At the same time the flow of vapor and steam is also downwardly in a circuitous path. The vapor entering through the riser 33 is deflected outwardly toward the periphery of the first pair of plates 31 and 32, then toward the center of the second pair of plates 41 and 42, then toward the outside of the third pair of plates, finally downwardly through the various pairs of plates to the steam outlet 59. The circuitous path of hot gases and vapor insures the heating of the vapor and steam to an extremely high temperature which produces a superheated steam at the steam outlet.

Further, to increase the efficiency of the steam transfer, a series of diffusers 66 which are frusto-conical and downwardly pointed depend from the first, third and fifth pairs of plates toward the circular hole 43 of the even-numbered pairs of plates. Diffusers 66 are held in position by rivets 65 attaching same to the odd-numbered plates. These diffusers help to deflect the gases in their proper path and also are heated thereby, the diffusers being welded to the lowermost of the odd-numbered pairs of plates, the heat absorbed by the diffusers being transmitted to the plates and hence assist in heating the vapor and steam in the water passageway.

An additional feature is the employment of long rivets 67 which pass through the pairs of plates, the shanks 68 extending beyond the bottom of the lower plate of each pair. These rivets also are heated by the passage of hot gases and the heat is transmitted to the vapor and steam in the passageways between the pairs of plates. The heads of the rivets 67 are welded to the top of the uppermost plate and the shanks 68 of the rivets are welded at their midpoints to the underside of the lowermost plate of the various pairs of plates so that steam will not escape through the rivet holes.

Further, to prevent escape of steam from the passageways between the pairs of plates, it will be noted that the joints 71 where the plates are joined are welded, the meeting edges of the adjacent plates being grooved in a 5 V-groove and filled by the weld.

Water vapor is injected in the inlet riser 33 through nozzle 34. The nozzle comprises a cylindrical housing 76 the lower end of which is threaded into the upper end of the riser 33. The housing is partially closed off 10 at the bottom by orifice plate 77 having a small-diameter circular hole 78 in the center. A needle 79 having a conical point 81 is disposed inside the housing 76 and held in position by guide 82, the needle being biased downwardly by spring 83, the tension of which is adjusted by screw 84, so that the point 81 is biased to close off the orifice 78. The middle of the shank of the needle is surrounded by a sleeve 86, there being a cylindrical annular passageway 87 between the outer diameter of the sleeve 86 and the inner diameter of the housing 76, and 15 20 the water inlet pipe 88 is connected into said annular cylindrical passageway. The water in pipe 88 is forced by means of a high-pressure pump 91 which may be a direct-action multiple reciprocating pump or gear pump. Adjustment screw 84 is regulative to hold the needle 79 closed until pressure of a predetermined amount builds up 25 in the chamber 89 at the lower end of the housing. When such pressure builds up sufficiently, the needle 79 rises against resistance of the spring 83 to the position shown in Fig. 1 and water is discharged through the orifice 78 30 in the bottom of the housing, the water passing downwardly through the inlet riser 33 in the vapor state. As soon as the pressure in chamber 89 falls below the predetermined amount set by the adjustment of screw 84, the valve closes. The operation of the nozzle is thus 35 such that the water is injected under a high pressure which causes the water to break up into a fine fog of vapor. The vapor of water is more efficiently heated than would be a stream or jet of water and further, the plates are less likely to be cracked if a fog of vapor is employed.

40 The control means for the device may be regulated by variations in the temperature of the uppermost pair of plates 31 and 32, the uppermost pair being the most accurate for such purpose. Accordingly, a pair of radially opposed studs 96 are fitted into sleeves 98 which pass 45 through apertures 97 in the casing. The inner ends of studs 96 are in contact with the top pair of plates 31 and 32, and said studs project outwardly through apertures 97 in the casing. Sleeve 98 surrounds the studs to prevent flame and hot gases from escaping through the aperture 50 in the casing and insulating material 99 surrounds the stud within the sleeve 98. Externally of the casing is a semi-circular yoke 101 affixed by bracket 102 to a stationary object. The outer ends of the yoke are pivotally connected by pins 103 to arcuate arms 104. The outer 55 ends of studs 96 bear against said arms 104 close to the pivot pins 103 so that a compound leverage arrangement produces a relatively greater movement of the remote ends of arms 104 for a small expansion or contraction of the studs 96. A control lever 106 is pivotally connected 60 by links 108 to the outer ends of the two arcuate arms 104. The point of connection of pivot pins 109 which connect lever 106 to links 108 is equidistant with respect to pivot pin 107. The effect of increase in temperature within the generator is to cause expansion of studs 96 65 which results, as clearly appears from Fig. 2, in a counter-clockwise movement of control lever 106, this movement being resisted by spring 111. Conversely, a cooling within the generator results in a clockwise movement of control lever 106. Control lever 106 may be connected 70 by means of a rod 112 which is pivotally connected at its outer end to valve 113 in gas intake line 16. By proper arrangement of leverage, the temperature within the generator may be maintained constant by the governing means heretofore described or other means which will 75 readily occur to one skilled in this art.

Although I have described my invention in some detail by way of illustration and example for purposes of clarity of understanding, it is understood that certain changes and modifications may be practiced within the spirit of the invention and scope of the appended claims.

What is claimed is:

1. A steam generator comprising a cylindrical casing, a burner in the first end of said casing, means for regulating the heat emitted from said burner, a flue for spent gases at the second end of said casing, a plurality of superposed pairs of plates mounted in said casing between said burner and said flue, each pair of plates being grooved out to provide an enclosed passageway for water-vapor and steam, a plurality of pipes providing communication from the passageway in one pair of plates to the passageway in the next pair of plates, said plates and pipes providing a circuitous pathway for water vapor and steam, one pair of plates being annular and its outer edge engaging said casing and the adjacent pair of plates being disk-shaped and its outer edge being spaced inwardly from said casing, conical diffusers projecting down from the bottom of a pair of disk-shaped plates into the hole in the underlying pair of annular plates thereby providing a circuitous pathway for hot gases produced by said burner, means for injecting water vapor in the passageway in the plates at the first end of said casing, said means including a high-pressure pump and a nozzle and a pipe connecting said pump and nozzle, and a steam discharge line communicating with the passageway in the pair of plates at the second end of said casing.

2. A steam generator comprising a cylindrical casing, a burner in the first end of said casing, means for regulating the heat emitted from said burner, a flue for spent gases at the second end of said casing, a plurality of coaxial pairs of plates mounted in said casing between said burner and said flue, each pair of plates being grooved out to provide an enclosed passageway for water-vapor and steam, a plurality of pipes providing communication from the passageway in one pair of plates to the passageway in the next pair of plates, said plates and pipes providing a circuitous pathway for water-vapor and steam, said plurality of coaxial pairs of plates being formed with an inner and an outer annular connecting ring and a thin radial connecting passageway, one set of said pipes connecting the outer annular ring of the first pair of plates with the outer annular ring of the second pair of plates, a second set of said pipes connecting the inner annular ring of said second pair of plates with the inner annular ring of the third pair of plates, means for injecting water vapor in the passageway in the plates at the first end of said casing, said means including a high-pressure pump and a nozzle and a pipe connecting said pump and nozzle, and a steam discharge line communicating with the passageway in the pair of plates at the second end of said casing.

3. A steam generator comprising a cylindrical casing, a burner in the first end of said casing, means for regulating the heat emitted from said burner, a flue for spent gases at the second end of said casing, a plurality of coaxial pairs of plates mounted in said casing between said burner and said flue, each pair of plates being grooved out to provide an enclosed passageway for water-vapor and steam, a plurality of pipes providing communication from the passageway in one pair of plates to the passageway in the next pair of plates, means for injecting water vapor in the passageway in the plates at the first end of said casing, said last mentioned means including a high-pressure pump and a nozzle and a pipe connecting said pump and nozzle, said means for injecting water vapor also comprising a housing, an orifice plate, means for conveying vapor discharged through the orifice in said plate to the nearest pair of plates, a needle, resilient means

biasing said needle to close off the orifice in said orifice plate, said housing being provided with a chamber behind said orifice, a sleeve reciprocable in said housing above said chamber and providing a guide for said needle, said sleeve being smaller than said chamber, means for supplying water under pressure into said chamber and a steam discharge line communicating with the passageway in the pair of plates at the second end of said casing.

4. A steam generator comprising a cylindrical casing, a burner in the first end of said casing, means for regulating the heat emitted from said burner, a flue for spent gases at the second end of said casing, a plurality of coaxial pairs of plates mounted in said casing between said burner and said flue, each pair of plates being grooved out to provide an enclosed passageway for water vapor and steam, a plurality of pipes providing communication from the passageway in one pair of plates to the passageway in the next pair of plates, means for injecting water vapor in the passageway in the plates at the first end of said casing, said means including a high-pressure pump and a nozzle and a pipe connecting said pump and nozzle, a steam discharge line communicating with the passageway in the pair of plates at the second end of said casing, a stud fixed to one of said pairs of plates and projecting out through said casing, a lever, means pivotally mounting said lever, said stud being positioned to engage said lever, resilient means biasing said lever into contact with said stud, whereby thermal changes within said casing cause expansion or contraction of said stud and cause pivotal movement of said lever, and means actuated by said lever for governing said means for regulating the heat emitted from said burner.

5. A steam generator comprising a cylindrical casing, a burner in the first end of said casing, means for regulating the heat emitted from said burner, a flue for spent gases at the second end of said casing, a plurality of coaxial pairs of plates mounted in said casing between said burner and said flue, each pair of plates being grooved out to provide an enclosed passageway for water-vapor and steam, a plurality of pipes providing communication from the passageway in one pair of plates to the passageway in the next pair of plates, means for injecting water-vapor in the passageway in the plates at the first end of said casing, said means including a high-compression pump and a nozzle and a pipe connecting said pump and nozzle, a steam discharge line communicating with the passageway in the pair of plates at the second end of said casing, a pair of diametrically opposed studs fixed to one of said pairs of plates and projecting out through said casing, in diametrically opposite directions, a yoke curved around half said casing, a pair of levers pivotally mounted on opposite ends of said yoke, said studs being positioned so that one stud engages one lever and the other stud the other lever, means biasing said levers into contact with said studs, whereby thermal changes within said casing cause expansion or contraction of said studs and cause pivotal movement of said levers, and means actuated by said levers for governing said means for regulating the heat emitted from said burner.
